UNITED STATES PATENT OFFICE

HARRY A. DOUGLAS, OF BRONSON, MICHIGAN

IGNITER

Application filed May 9, 1929. Serial No. 361,672.

My invention relates to igniters, the invention being of particular service in connection with those igniters that are known as cigar or cigarette lighters.

My present invention embraces modifications of features of construction of an igniter forming the subject matter of my co-pending application Serial No. 361,671, filed May 9, 1929. The igniter disclosed in my aforesaid co-pending application is inclusive of an inflammable element, a casing in which said member is removably contained, igniting mechanism in igniting relation to said inflammable element, and a retainer engaging and positioned by the container and in holding relation to the aforesaid member, this retainer being shiftable to permit removal and replacement of this member, said igniting mechanism being assembled with said retainer and positioned thereby in cooperative relation with the aforesaid inflammable element. The mechanism of my present invention desirably includes such a retainer, though the invention is not to be thus limited. The mechanism of my present invention also includes a lever pivoted upon the casing and upon the retainer, if such be employed, a spring for operating the lever and attached thereto at one side of the lever pivot, a latch upon the casing for positioning the lever against the force of the spring, a striker coupled with the lever to be operable by the lever when the lever is released by the latch, a body of spark producing material engageable by the striker, when thus operated, to produce sparks, and an inflammable element in the region of said body of spark producing material to receive igniting sparks therefrom. In accordance with my present invention the spring which operates the lever also serves to place the latch in a lever holding position.

The invention will be more fully explained in connection with the accompanying drawings in which Fig. 1 is a view of an upper portion of the igniter of my invention, parts being shown in sectional elevation and parts in full elevation, this figure being generally taken on line 1—1 of Fig. 2; Fig. 2 is a sectional view on line 2—2 of Fig. 1; Fig. 3 is a

view, mainly in elevation, of the igniter portion shown in Fig. 1, a few parts being shown in section; Fig. 4 is a view in elevation of an igniter on a smaller scale, a portion being shown in section; Fig. 5 is a top view of the igniter shown in Fig. 4; Fig. 6 is an end view of the structure as shown in Fig. 3; Fig. 7 is a view generally taken on line 7—7 of Fig. 1; Fig. 8 is a sectional view on line 8—8 of Fig. 1; Fig. 9 is a sectional view on line 9—9 of Fig. 1; Fig. 10 is a view, in elevation, of the preferred form of fuel member, parts being broken away and shown in section; Fig. 11 is a sectional view on line 11—11 of Fig. 1; and Fig. 12 is a view of part of the structure generally taken on line 12—12 of Fig. 1.

The fuel member illustrated is inclusive of a container 1 for the liquid fuel 2. This container has a cover 3 permanently secured thereto. This cover is furnished with an interiorly threaded bushing 4 that passes through an opening in the cover and receives a threaded closure plug 5. This closure plug has a flange 6 which presses a sealing gasket 7 upon the bushing. Fuel is admitted to the container through the opening occupied by the plug. Fuel is discharged from the container by means of a wick 8 that reaches the bottom of the container and passes through another opening in the cover 3, this latter opening receiving another bushing 9 through which the wick passes. The bushing 9 has an upwardly extending slightly tapering continuation 10. An upright elongated bushing 11 has its lower end clinched into the border of the portion 10 that surrounds an opening at the upper end of this portion. The part 11 snugly surrounds the upper end of the wick to position it sufficiently close to the spark emanating portion of the igniting mechanism. When containers of the construction described are carried in stock, each is supplied with a cap 12 whose skirt snugly engages the bushing portion 10 to guard against the escape of liquid fuel.

When the container is inserted within the body 13 of the casing of an igniter the cap 12 is removed, this cap being replaced by a snuffer 14 that is placed in sealing engagement with the bushing portion 10 when the

igniter is not in use and which is removed from such engagement when the wick is to be lighted, as will more fully hereinafter appear. The casing also includes a retainer 15 which is preferably in the form of a lid for the casing body. Said lid is somewhat in the form of an inverted cup whose bottom edge or rim is tightly and telescopically received within the upper end of the casing body, this 10 rim then engaging the bead 17 which is formed upon and about the upper end of the fuel container, said lid then preventing the container from being displaced upwardly. A leaf spring 18 is secured, at one end, within 15 the casing body and upon its bottom wall, this spring being depressed by the lid, when closed, through the intermediation of the fuel container to prevent the fuel container from moving about within the casing, the spring 20 compensating for some inequalities that may occur in manufacture. When the fuel container within the casing is to be replaced the lid is removed from the casing body.

The retainer or lid 15 desirably constitutes 25 a carrier for all of the parts of the igniting mechanism, though the invention is not to be thus limited. The igniting mechanism illustrated is inclusive of a block 19 of pyrophoric material, preferably flint, which is 30 normally substantially stationary with respect to the container and the wick or inflammable element 8 where it issues from the container. This relationship of this block and the wick is desirably normally maintained by 35 placing the block within a horizontally disposed socket 20 which is formed in the front wall portion 15' of the lid 15. The igniting mechanism also includes a striker 21 which is preferably in the form of a bar of hard 40 metal having a serrated face that is opposed to and engages one end of the block 19. This striking bar is received within the channel of an arm 22 that is of U-shape in cross section with the U turned ninety degrees. 45 The striking bar is caught between the deflected end portion 23 of said arm and the tongue 24 which is struck from the arm into its channel. The arm 22 is moved to the right when the igniter is used for its purpose. It 50 is guided in its movement, at its right hand end, by the flint block 19 and a part 15' of the lid. A leaf spring 25 is anchored, at one end, to a side of the cover 15 and presses, at its unmounted end, against the block 19 55 to maintain the block in engagement with the striking bar and to feed the block through the socket 20 as the block becomes worn by said bar. The unmounted end of spring 25 may be moved to one side and downwardly, 60 the spring being pivotally anchored, when it is desired to replace the flint body 19. The arm 22 is pivotally mounted at 26 upon the lever 27. This lever is in the form of a bell crank having pivotal connection, at 28, 65 with lid 15.

A coiled spring 29 is anchored, at its front end, to the ear 30' upon latch 30 and is attached, at its rear end, to the depending arm of the bell crank 27. Said spring pulls upon the aforesaid lever in a counterclockwise direction, the lever being held in its depressed position by the latch 30 which is carried by the lid portion 15'. This lid portion is angular and depressed below the top level of the lid and inwardly offset with respect 75 to the contiguous upright side of the casing body 13 and the right hand end of the lever 27 to afford a chamber in which the upper end of the wick, the bushing portion 11 and the upper part of the bushing portion 10 are 80 received. This latter bushing portion extends through an opening in the horizontal part of the wall portion 15', the latch being in sliding relation to this horizontal wall part. The latch 30 is provided with a bent lug 30' that 85 has a portion inserted beneath the continuation 15' of the lid part 15' and a portion in fulcrum engagement with a side of the part 15'. The spring 29 thus not only serves to 90 operate the lever 27, as will appear, but also 95 serves to pull upon the latch 30 in a counterclockwise direction normally to hold it above the nose 27' of the lever 27 to maintain this lever latched. When the bell crank lever 27 is held depressed by the latch 30, the snuffer 100 14 snugly engages the top of the bushing portion 10 to extinguish the flame that was previously produced in a manner which may be apparent, but which will later be described, and to prevent the evaporation and escape of the liquid fuel from the wick. When the latch is moved to the left to clear the nose 27' the lever is released and is turned counterclockwise by the spring 29. When the lever is thus operated the arm 22 is moved forwardly to scrape the serrated face of the striking bar 21 across the adjacent end of the flint block 19. The sparks which arise at the flint block have access to the wick which is consequently ignited. 110

The lever 27 is desirably of T form, the stem of the T substantially filling the slot that is formed in the top of the lid 15. The head of the T fits into the angular recess afforded by the wall portion 15' of the lid 15 and rounds out the appearance of the device as indicated in Figs. 4 and 5. The T head is below to enclose the snuffer and the inflammable end of the wick. 115

Changes may be made without departing from the invention. 120

Having thus described my invention, I claim:

1. An igniter including a casing; a lever pivoted upon the casing; a spring for operating the lever; a latch upon the casing for positioning the lever against the force of the spring, said spring being connected with the lever at one end and with the latch at its other end and normally operating upon the latch 125 130

to position the latch in a lever retaining position; a striker operable by the lever when the lever is released by the latch; a body of spark producing material engageable by the striker, when thus operated, to produce sparks; and an inflammable element in the region of said body of spark producing material to receive igniting sparks therefrom.

2. An igniter including a casing; an intermediate pivoted lever upon the casing; a spring for operating the lever and attached thereto at one side of the lever pivot; a latch upon the casing for positioning the lever against the force of the spring, said spring being connected with the lever at one end and with the latch at its other end and normally operating upon the latch to position the latch in a lever retaining position; a striker coupled with the lever to be operable by the lever when the lever is released by the latch; a body of spark producing material engageable by the striker, when thus operated, to produce sparks; and an inflammable element in the region of said body of spark producing material to receive igniting sparks therefrom.

3. The structure of claim 1 wherein the latch is fulcrumed and is turned by the spring to lever retaining position.

- 30 4. The structure of claim 2 wherein the latch is fulcrumed and is turned by the spring to lever retaining position.

In witness whereof, I hereunto subscribe my name.

HARRY A. DOUGLAS.
